(57) **CLAIM**

The ornamental design for packaging cartons, as shown and described.

DESCRIPTION

FIG. 1 is a top perspective view from above of a packaging carton for containing product showing my new design.

FIG. 2 is a top plan view thereof.

FIG. 3 is a bottom plan view thereof.

FIG. 4 is a side view thereof.

FIG. 5 is a right end view, the left end being identical thereof.

FIG. 6 is a close-up view of the fin end seal thereof. .

FIG. 7 is a perspective view thereof showing the pack in an expanded configuration.

FIG. 8 is a perspective view of a pack in a multiple pack alternative configuration.

FIG. 9 is a plan view of the multiple pack thereof in a multiple pack alternative configuration.

FIG. 10 is a plan view from below of the multiple pack thereof in a multiple pack alternative configuration.

FIG. 11 is a side view of the multiple pack thereof in a multiple pack alternative configuration.

FIG. 12 is a right end view of the multiple pack, the left end view being identical in a multiple pack alternative configuration.

FIG. 13 is a close-up view of the fin end seal of the multiple pack in a multiple pack alternative configuration.

FIG. 14 is a perspective view of the multiple pack, showing the pack in an expanded configuration in a multiple pack alternative configuration.

FIG. 15 is a right end view of the multiple pack in a folded configuration, the left end view being identical in a multiple pack alternative configuration.

FIG. 16 is a right end view of the multiple pack in a folded configuration, the left end view being identical in a multiple pack alternative configuration; and,

FIG. 17 is a perspective view of the multiple pack in a rolled configuration in a multiple pack alternative configuration.

The broken lines shown in the drawings are for illustrative purposes only and form no part of the claimed design.

Although the multiple pack is illustrated as being made up of six individual packs, other numbers of individual packs would make the same overall impression and therefore the design is not restricted to the number being six.

It will also be appreciated that the multiple pack can be rolled up or folded in any way and therefore the design is not restricted to the pack being provided in a flat configuration as illustrated or in the particular folded or rolled configurations as illustrated.

No claim is made to the size or relative dimensions of the product. In particular, various ratios of length: width: depth could be used.
